UNITED STATES PATENT OFFICE.

BERT C. DRAKE, OF WAUBAY, SOUTH DAKOTA.

BINDER ATTACHMENT.

1,165,370.

Specification of Letters Patent.

Patented Dec. 21, 1915.

Application filed July 7, 1914. Serial No. 849,594.

To all whom it may concern:

Be it known that I, BERT C. DRAKE, a citizen of the United States, residing at Waubay, in the county of Day, State of South Dakota, have invented certain new and useful Improvements in Binder Attachments; and I do hereby declare the following to be a full, clear, and exact description of the invention, such as will enable others skilled in the art to which it appertains to make and use the same.

This invention relates to a binder attachment.

An object of the invention is to provide means on the binder for varying the speed with which the binder head operates.

With this and other objects in view, such as will appear as the description progresses, my invention comprises the combination and arrangement of parts as herein set forth and subsequently claimed:

Referring to the drawing: Figure 1 is a side elevation of a portion of a binder with my device in place thereon. Fig. 2 is a plan view of my device, the portion of the binder being in section showing the gears in such relation that the binder head will be operated at low speed. Fig. 3 is a similar view, showing the gears shifted to operate the binder head at high speed. Fig. 4 is a sectional view on line 4-4 of Fig. 2. Fig. 5 is a sectional view on line 5-5 of Fig. 2. Fig. 6 is a detail of the shifting gears and means for shifting the same. Fig. 7 is a fragmental sectional view.

Referring to the drawing by reference characters wherein like parts are indicated by like characters throughout the several views, the binder is indicated generally by the reference character 1 and the head by reference character 2. A drive chain 3 from the main drive shaft of the binder passes over sprockets 4 and 5, the sprocket 4 being mounted on a shaft 6 fixed in bearings to the binder. One end of the shaft 6 is supported in a bearing box 7 in a bracket 8, which bracket is secured to the lowermost platform 9 of the binder. Fixed to this shaft 6 is a gear wheel 7' having teeth 8' on one side thereof which teeth mesh with teeth 9' on the side of an additional gear 10, which gear is mounted on a shaft 11 and free to rotate thereon, but held against sliding movement on the said shaft by collars 12 which bear against the sides of the said gear 10. This gear 10 is provided with

additional teeth 13 on the opposite side thereof. Slidably mounted and free to rotate on the shaft 11 is a gear 14, which has teeth 15 on one of its faces around the edge 60 thereof and teeth 16 on the other face, which teeth extend completely around the face. The shaft 11 is extended beyond this gear and has fixed thereto at its extremity a small clutch number 17 having teeth 18 on its face 65 adjacent the gear 14. This gear 14 has sprocket teeth 19 formed on its periphery and a chain 20 is mounted on the gear so as to be in contact with the sprocket teeth. This chain passes about the binder head 70 sprocket 21, which is slidably keyed on a shaft 22. A forked link 23 is engaged at one of its ends with the gear 14 and its other end with the sprocket 21. Secured to this link 23 is a chain tightener 24 which engages the chain 20 for maintaining the same in tight relation to its driving gear and sprocket. A rod 25 is attached to the link 23 and extends to the side of the machine so that the gear 14 and the sprocket 21 may 75 be shifted on the shafts 11 and 22, respectively.

It is to be noted that the sprockets 4 and 5 are of equal diameters so that the shafts 6 and 11 will be driven at the same speed. 85 The change in speed of the sprocket 14 is due, however, to the fact that when it is driven by the shaft 11 it will be connected directly to this shaft by the clutch member 18, but when it is driven by the shaft 6 it 90 will be connected to this shaft by means of the intermeshing gears 7' and 10, the relative size of which controls the speed. The chain 3 through its connection with the sprockets 4 and 5 normally rotates the shafts 95 6 and 11, respectively, so that the gear 7 and clutch member 17 are normally rotated, the same being fixed to the said shafts. By virtue of the engagement of the gear 7' with the gear 10, this latter gear which is loose 100 on the shaft 11 is rotated.

When it is desired to operate the binder head at slow speed the rod 25 is pulled outwardly from the machine, which shifts the gear 14 toward the gear 10 until the teeth 105 15 thereon engage the teeth 13 of the adjacent face of the gear 10, the said gear 14 is then rotated loosely on the shaft 11 and through its connection with the sprocket 21 operates the binder head. When it is desired 110 to operate the binder head at high speed the rod 25 is pushed inwardly on the machine,

thus shifting the gear 14 until the teeth 16 thereon engage with the teeth 18 on the small clutch member 17. The rotation of the shaft 11 then causes, through the operative connection between the gear 14 and the sprocket 21, the binder head to operate at high speed.

From the foregoing description it may be seen that I have provided a device which 10 will operate the head of a binder at a plurality of speeds so that the speed may be reduced when cutting thin or short grain and it may be increased when cutting heavy or long grain.

15 While I have shown a particular embodiment of my invention, I do not wish to be limited to that particular embodiment for it is obvious that numerous changes may be made within the scope of the invention as 20 defined by the claims.

What is claimed is:—

1. In combination with a binder frame, a binder head, a sprocket connected to and arranged to actuate said head, a drive shaft, 25 a sprocket slidably mounted thereon and rotatable independently thereof, the said sprocket having gear teeth on the side faces thereof, a chain passing over said first mentioned sprocket and said last mentioned 30 sprocket, a clutch member secured to the drive shaft and arranged to engage the gear teeth on one side of the last mentioned sprocket, a second drive shaft, a gear secured

to said second drive shaft and a gear intermeshing with the last mentioned gear and 35 arranged to intermesh with the teeth on the other side of the second mentioned sprocket, whereby upon the rotation of the second drive shaft the said sprocket will be rotated independently of the first mentioned drive 40 shaft.

2. In combination with a binder frame, a binder head thereon, a shaft mounted on the frame, a sprocket wheel slidably mounted on said shaft and rotatable independently 45 thereof, means connecting the sprocket and the head to operate the latter, a driving shaft, a sprocket slidably mounted thereon, a chain passing over said first mentioned and last mentioned sprockets, a clutch member secured to said drive shaft to one side of the last mentioned sprocket, a gear rotatably mounted on the said drive shaft to the other side of said sprocket, means for driving the 50 said gear at different speed from the drive shaft and clutch member, and means for selectively shifting the last mentioned sprocket into engagement with the clutch member or the gear.

In testimony whereof, I affix my signature, in the presence of two witnesses.

BERT C. DRAKE.
